POWER OPERATED WINDOW REGULATOR

John W. Lakin, Detroit, Mich., assignor to
Ternstedt Manufacturing Company, Detroit,
Mich., a corporation of Michigan

Application March 27, 1942, Serial No. 436,478

3 Claims. (Cl. 268—119)

This invention relates to an electrically operated window regulator for operating the swinging panel of a Fisher "No-Draft" ventilating system.

In recent years the no-draft ventilating system has been used for the windows of the front doors of automobiles. This comprises a rear vertical sliding panel and a front swinging panel. The front panel swings on an intermediate axis. The front and rear panels are ordinarily operated with separate hand cranks. However, with the type of torpedo bodies that have been used in the last two or three years, the bodies are so wide that it is very inconvenient for the driver to reach across and operate the cranks on the curb door. On this account power operated window regulators have been introduced, but these power operated window regulators are designed to operate only the rear vertical sliding panel.

It is the object of the present invention to afford a power operated mechanism for operating the swinging panel. One of the objects of the invention is to provide apparatus which has increasingly greater mechanical advantage as the window closes so as to be able to provide the greatest force in jamming the window against the rubber weatherstrips. Another object is to provide mechanism in which there is an automatic lock so it is practically impossible, if not impossible, to pry the window open to get a wire into the car for the purpose of operating the inside handle opening the door.

Referring to the drawings:

Fig. 1 is a plan view of one form of the invention.

Fig. 2 is an elevation of the same.

Fig. 3 is an end elevation of the same showing the apparatus mounted in the door well.

Fig. 4 is a vertical section.

Fig. 5 is a fragmentary side elevation of an automobile showing the Fisher "No-Draft" ventilating system.

Fig. 6 is a plan view of a modified form of the invention.

Fig. 7 is an elevation of this modified form of the apparatus.

Referring to Fig. 5, 1 designates the sliding rear panel of the Fisher "No-Draft" ventilating system. 2 designates the swinging panel of this ventilating system which is power operated by the electric motor M in a way now to be described.

Referring to Fig. 2, M is the motor which has a coupling 3 with a shaft 4 on which is a driving worm 5 that meshes with the worm gear 6. On the worm gear shaft 7 is another worm 8 which

drives the worm gear 9 which is attached to shaft 10. Referring to Fig. 1, on the upper end of this shaft is a crank 11 which has its end connected with a rack 12 by means of the pivot pin 13. This rack is guided in a loop-like guide 14 which is pivoted on the shaft 15 and holds the rack teeth in engagement with the teeth of a gear 16. This gear 16 is fastened to the shaft 15 which in turn is bolted to the spindle 17 of the ventilating panel by the bolt 18.

When the electric motor is started by a push button, not shown, but which will be located on the instrument board or inside of the door panel, the worm gearing turns, causing a considerable reduction in the movement and increasing the mechanical advantage. Referring to Fig. 1, the dotted-line showing of the rack 12 and the crank 11 shows the position of the parts when the ventilating panel is in open position. These panels turn in the neighborhood of 110° or somewhat beyond a perpendicular position. The shaft 10 revolves slowly swinging the crank from the dotted-line position to the full-line position shown in Fig. 1. In this position the rack 12 and the crank 11 form a pair of toggle arms which are on substantially the center-line position. Consequently, it is impossible to open the window by prying it open. Furthermore, as the crank arm approaches the straight-line position with the rack 12, the mechanical advantage of the crank arm is greatly increased in accordance with the usual operation of a pair of toggle arms. At the same time the movement of the rack is very materially slowed up. This is very advantageous to provide a relatively large force to close the panel tightly against the rubber weatherstrip 34 and provide an efficient weather seal.

Referring to Figs. 6 and 7 a modified form of apparatus which provides these same objectives is shown. Here a motor has a worm 19 which meshes with worm gear 20, driving shaft 21 and worm 22 which meshes with worm gears 23 and 24. Worm gear 23 is attached to an operating shaft 25 in the upper end of which is a socket 26 for receiving the spindle of the ventilating panel, such a spindle as is shown at 17 in Fig. 2. Here is a direct worm gear drive from the motor to the operating shaft which operates the ventilating panel spindle. In order to provide a greater mechanical advantage as afforded by the toggle arrangement described, in the first form of the invention worm gear 24 drives a crank 21 fastened to the end of the shaft 28. Crank 27 is provided with a crank pin 29 which engages the arm 30 of lever 31. Lever 31 is connected

with a crank arm 32 which is secured on the end of the operating shaft 25. A link 33 connects the end of lever 31 with crank 32 forming a toggle. As gear 24 is revolved, at the same time the gear 23 is revolved by a worm 22, this crank pin 29 strikes the jaw 30 of toggle arm 31 during the last stages of the movement of the parts and applies a right-angular thrust to the toggle arms and, consequently, affords a relatively great mechanical advantage. This arrangement, therefore, provides a relatively great force for closing the window against the rubber sealing strips, such as shown at 34 in Fig. 3, but in a different way than that shown in the toggle arrangement shown in Fig. 1.

What I claim is:

1. In a power operated apparatus for closing a swinging panel in a no-draft ventilating system, the combination of a shaft rotatably supported and having thereon a gear, said shaft arranged for connection with the spindle of a swinging ventilating panel, a crank arm pivotally supported, a toothed rack having a pivotal connection with the end of the crank arm to form with the crank arm a toggle and having its teeth held in mesh with the teeth of the said gear, reduction gearing for driving said crank arm and a motor for operating the reduction gearing, the said crank arm and rack turning through approximately 90° or more to a position where they are substantially in a straight-line position to afford a lock for the swinging panel and also a relatively great mechanical advantage in closing the window in the final stages.

2. In a power operated apparatus for closing a swinging panel in a no-draft ventilating system,

the combination of a shaft rotatably supported and having thereon a gear, said shaft arranged for connection with the spindle of a swinging ventilating panel, a crank arm pivotally supported, a toothed rack having a pivotal connection with the end of the crank arm to form with the crank arm a toggle and having its teeth held in mesh with the teeth of the said gear, a loop-like member pivoted on said shaft and embracing said rack for holding the teeth of the rack in engagement with the teeth of said gear, reduction gearing for driving said crank arm and a motor for operating the reduction gearing, the said crank arm and rack turning through approximately 90° or more to a position where they are substantially in a straight-line position to afford a lock for the swinging panel and also a relatively great mechanical advantage in closing the window in the final stages.

3. In apparatus for closing a swinging panel in a no-draft ventilating system, the combination of a shaft rotatably supported and having thereon a gear, said shaft arranged for connection with the spindle of a swinging ventilating panel, a crank arm rotatably supported, a toothed rack having a connection with the end of the crank arm to form with the crank arm a toggle and having its teeth held in mesh with the teeth of the said gear, reduction gearing for driving said crank arm, the said crank arm and rack turning through an arc to a position where they are substantially in a straight-line position to afford a lock for the swinging panel and also a relatively great mechanical advantage in closing the window in the final stages.

JOHN W. LAKIN.
